Des. 177,068
Patented Mar. 6, 1956

177,068

NECKLACE OR LIKE ARTICLE

John Roberts, Honolulu, Territory of Hawaii
Application January 6, 1955, Serial No. 33,857

Term of patent 14 years

(Cl. D45—16)

Fig. 1.

Fig. 2.

Fig. 3.

What I claim is:

The ornamental design for a necklace or like article, as shown.
